E. W. THOMAS

OIL BURNER

Filed Sept. 9, 1922

EDWARD W. THOMAS, Inventor

Jesse P. Stone

his Attorney

UNITED STATES PATENT OFFICE.

EDWARD W. THOMAS, OF HOUSTON, TEXAS.

OIL BURNER.

Application filed September 9, 1922. Serial No. 587,182.

To all whom it may concern:

Be it known that I, EDWARD W. THOMAS, a citizen of the United States, residing at Houston, Harris County, Texas, have invented a certain new and useful Improvement in Oil Burners, of which the following is a full, clear, and exact description, such as will enable others skilled in the art to which it appertains to make and use the same.

My invention relates to oil burners for use in spraying oil in furnaces.

The object of my invention is to provide an oil burner for the purpose stated, which may be used for either force or gravity feed, and which will thereby be adapted for employment either on stationary or locomotive boilers.

A further object of my invention is to provide an oil burner wherein the oil is discharged from the burner by an ejector effect through the force of a jet of steam, in the most efficient manner.

Another object is to provide a passage for the steam through the burner nozzle which will allow the use of the steam at a high temperature, whereby the most efficient effect may be obtained.

It is a further object of my invention to so construct the burner in a plurality of parts that the same may be made fluid-tight and may be cleaned or repaired without difficulty when necessity arises.

It is also an object of my invention to form a removable wear plate upon the lip of the nozzle in such manner as to make said plate removable and replaceable when wear occurs. These and other objects and advantages will most clearly appear from the more detailed description which follows, and the points of novelty therein will be set forth with more particularity in the claims appended hereto.

Referring to the drawing herewith wherein a preferred embodiment of my invention is disclosed, Fig. 1 is a perspective view of my improved nozzle, showing the manner in which it is connected up. Fig. 2 is a central vertical section through the nozzle. Figs. 3 and 4 are perspective views showing the construction of the lip of the spraying nozzle used with my invention, and Fig. 5 shows a wear plate which I employ.

In forming this improved type of nozzle I employ an upper oil-conducting chamber,

1. This chamber is approximately rectangular in shape, having the rearward end extending upwardly slightly at 2, and having a threaded opening 3 therein for connection with an oil-conducting pipe 4 extending to 60 an oil supply tank, not shown. The chamber is somewhat flattened internally at 5 and the forward end thereof is flared outwardly and provided with openings at 6 through which bolts or screws 7 may be inserted for the purpose of securing the nozzle in assembled position. The forward end is curved and extended upwardly slightly at 8. Spaced back slightly from the forward curved end of the chamber, I provide a 70 downwardly directed opening 9 for the discharge of oil from the chamber.

The oil is drawn from the chamber and discharged by means of a jet of steam, and to provide a passage for this steam to the forward end of the nozzle I form a chamber 10 similar in general outline to the oil chamber 5. It has a threaded opening 11 at the rearward end for connection with a steam-conducting pipe 12, having connection with a steam boiler or other source of steam supply. The chamber is flattened similar to the one above, and is spaced slightly from the chamber 5 by the thickening of the walls of the two chambers at 12 at the rearward end, and by means of a spraying plate 13 toward the forward end, which plate will be later described. The forward end of the chamber 10 is provided with a separating wall 14 connected at 15 with the upper wall 30 of the chamber extending downwardly and then forwardly to a point spaced slightly from the forward wall 16 of the chamber. By this means the passage of steam through the chamber 10 is directed downwardly below the wall 14 around the forward end thereof, and then upwardly through an opening 17 in the upper wall of the chamber immediately below the opening 9 in the oil chamber above.

The steam chamber and the oil chamber are spaced slightly from each other at the forward end by the spraying plate 13. This plate is shown in detail in Figs. 3 and 4. It is of the same width as the forward end of the nozzle and extends forward so as to lie flush with the forward face 16 of the steam chamber. It will be noted that this face of the steam chamber projects slightly beyond the forward wall of the oil chamber. The 110

upper surface of the plate 13 is cut away centrally thereof to provide a downwardly extending recess 18 terminating at the lip 19 over which the oil is allowed to run. A 5 curved connecting member 20 is formed above and slightly forward of the lip 19 to connect the two sides of the plate as shown in Fig. 3, and to limit the discharge opening of the fuel. This connecting member is it- 10 self spaced slightly rearwardly from the forward end of the plate and the sides of the opening in front of the lip are inclined or beveled outwardly at 21 so as to form a fan-shaped opening for the discharge of the oil 15 into the combustion chamber.

On the lower side of the plate 13 is formed a similar recess 22, beveled upwardly and terminating in a downwardly extending flange 23 of short length, between which and 20 the upper face of the oil chamber below is formed a constricted flattened passage 24 for the steam. The discharge of steam under pressure from this constricted passage has been found to wear the surface of the plate 25 somewhat, and I therefore contemplate the provision of a removable wear plate 30 of hardened steel between the lower face of the plate 13 and the chamber 10. This plate is shaped to fit the plate 13 and has an opening 30 25 therein registering with the opening 17 to allow the exit of steam. This plate will protect the steam chamber surface from wear and may be replaced when worn.

In the operation of this device the oil is 35 ordinarily admitted by gravity through the pipe 4 into the chamber 5 of the burner through which it passes to the opening 9 and downwardly upon the beveled discharge plate at 18. The steam entering through the 40 pipe 12 to the lower chamber 10, passes around the forward end of the baffle 14 and upwardly through the opening 17, into the space below the plate 13, and issues under pressure through the constricted passage 24 45 and outwardly through the fan-shaped opening in the nozzle. This steam, ejected with force, acts as an ejector to draw the fuel oil outwardly from the chamber 5 above. It will thus be noted that the oil will be blown 50 from the nozzle of the burner by the force of the steam, even though it enters the nozzle simply by the force of gravity. The oil will flow downwardly over the lip 19 in a thin film, and will be caught by the steam and 55 discharged with great force through the forward opening at 21, and will issue in a fan-shaped spray into the fire box. A narrow passage between the walls 21 will be sufficient to accommodate a large amount of oil 60 when thus discharged with great force. The nozzle itself is set in the rear end of the fire box and will be heated to a high temperature by the combustion within the furnace. The 65 passage of the steam below the separating wall or baffle 14 in the forward end of the

nozzle and around the forward end of said wall, will allow the steam to be somewhat super-heated to a high temperature before it issues beneath the lip 19. It will therefore be a dry steam, and will be projected out 70 under high pressure. This atomizes and gasifies the oil and facilitates the action of the nozzle to a marked degree.

The formation of the burner in two sections as shown, makes it possible to construct the burner most effectively, and will allow for expansion and contraction under heat, thus preventing cracking. No opening for leakage of gas about the burner will be allowed, and defects in the burner where- 75 by gas might escape may be easily remedied. The removable spraying plate 13 is secured firmly in position between the two parts of the nozzle when the screws or bolts 7 are extended downwardly through the two parts 80 of the burner and the plate, and no tendency for leakage about the nozzle will exist. When it is desirable at any time to clean the parts of the burner, this may be done through the provision of an opening at 85 26 toward the rearward end of the oil chamber. This opening will be closed by screw-threaded plug 27, under ordinary circum- 90 stances, but this plug may be removed and a steam jet inserted in said opening and the 95 chamber 5 thoroughly cleaned, even when the burner is operating. The lower steam chamber 10 may be also cleaned at its for- 100 ward end by a similar opening 28, closed by the plug 29.

The use of this type of burner will make it possible to use heavy grades of oil without the necessity of heating such oil beyond the ordinary atmospheric temperature. This is due largely to the efficient action of 105 the steam jet and the construction of the nozzle whereby the ejector action is exerted upon the oil as it is drawn downwardly over the lip 19. I have thus provided a strong and efficient burner which may be economi- 110 cally constructed and which will last for long periods of time without danger of getting out of order. The further objects and advantages will be apparent to one skilled in the art without further description.

What I claim is new and desire to protect by Letters Patent is:

1. An oil burner comprising two separable chambers, an upper oil chamber connected at its rear end to a source of supply of oil and having a downwardly directed discharge opening at the forward end, a lower chamber connected with a source of steam and having an upwardly directed opening at its forward end, a removable spray plate between said openings, there being an oil conducting passage, the lower side of which terminates in a spray lip on the upper side of said plate, and a constricted passage below said lip for the steam, said burner hav- 120 125 130 135 140 145 150 155 160 165 170 175 180

ing a fan-shaped flattened orifice at the mouth of the burner for the discharge of the spray.

2. An oil burner comprising an upper oil chamber, a lower steam chamber, said chambers having opposite discharge openings adjacent their forward ends, a spray plate between said openings acting to space said chambers apart, there being a downwardly inclined oil channel on the upper face of said plate terminating above a lip on said plate, and a constricted passage for steam below said lip on the under side of said plate, the walls of said plate diverging in front of said lip to form a discharge nozzle.

3. An oil burner comprising oil and steam chambers extending longitudinally thereof, said chambers being spaced slightly apart centrally, a spray plate fitting closely between the forward ends thereof, said cham-

bers having discharge openings directed upon said plate, a forwardly inclined lip on the upper side of said plate, a flattened constricted channel on the opposite side of said lip for the steam, whereby the discharge of steam under pressure will draw oil from said oil chamber and spray it from the burner.

4. In an oil burner, the combination of an oil discharge member, an adjacent steam discharge member, a spray plate between said discharge members, a lip on said plate for said oil, means in said steam discharge member to increase the length of the passage of steam therethrough, and means to direct said oil and steam from said burner in a flattened fan-shaped spray.

In testimony whereof, I hereunto affix my signature this the 5th day of September, 1922.

EDWARD W. THOMAS.
